UNITED STATES PATENT OFFICE

JOHN J. LYTH, OF VALLEYFIELD, QUEBEC, CANADA

APPARATUS FOR AND PROCESS OF PILING ROPED CLOTH ON A CIRCULAR AREA

Application filed September 13, 1926, Serial No. 135,127, and in Great Britain September 4, 1925.

This invention relates broadly to improvements in apparatus for and process of piling roped cloth on a circular area, for example, in a cylindrical kier, and relates more particularly to improvements in the apparatus disclosed in my former Letters Patent No. 1,528,065 granted 3rd March 1925.

The primary object of the invention is to provide a cloth piling machine materially simplified in construction, of less weight and capable of being manufactured at smaller cost, all as compared with apparatus previously identified.

A further object is to provide a machine so constructed and arranged that it projects only a minimum distance into a kier, thus permitting the cloth to be piled to a maximum depth in the kier.

A still further object is to provide in a machine of the type embodying a chute swinging or oscillating in vertical planes, means for automatically controlling the swing of the spout to ensure delivery of the cloth at the wall of the kier at all levels and yet capable of manual control.

Another object is to provide in a machine of the type last mentioned a chute so arranged that in swinging it does not exert any lifting effect on the cloth.

Still another object is to provide a machine of the type embodying a chute swinging in vertical planes, which will pile cloth accurately along a predetermined path, avoiding a constant retracing of the path, and maintain the top of the pile approximately level, or which will in the course of filling a kier automatically average up departures from level piling so that, when the kier is filled, the top of the pile will be level or slightly mounded in the centre, which is desirable.

Various other objects and advantages additional to those disclosed in my former patent may be ascertained from the following description and accompanying drawings.

In circular cloth piling machines formerly devised by me, the cloth has been passed through a revolving jointed conduit including a vertical rotatable portion swinging a lateral extension in a horizontal plane. This ex-

tension terminated in a downturned outlet designed to direct the cloth vertically downward, so that the path along which the cloth was piled was an exact replica of the path traced by the conduit outlet, with the result that very accurate piling could be obtained. Because of practical limitations (principally the relation of the diameter of a kier mouth to the diameter of the kier itself), the realization of piling as aforesaid entailed the employment of much mechanism and necessitated projection of the conduit for an appreciable distance downwardly into the kier.

According to the present invention, a revolving conduit is employed embracing only two sections, namely, an upper vertical section and a lower section or chute telescopically related to the upper section and swinging in vertical planes. The conduit is supported and revolved by mechanism similar in its essentials to that disclosed in my former patent already identified, but the manner of operating the conduit is radically different.

If a normally vertical chute swings or oscillates from a horizontal axis near its upper end, it will be apparent that as the chute swings outwardly its lower end will rise and, as it approaches horizontal position, will exert a gradually increasing lifting effort on cloth passing through it. This materially increases the power required for operation, invites clogging with cloth at the outward extreme of movement and, what is most undesirable, necessitates a considerable downward projection of the chute into the kier in order that the necessary amplitude of swing may be obtained without the chute striking the shoulder of the kier. I have obviated all these disadvantages by so arranging the mechanism that the chute swings from a centre descending during the outward swing and vice versa, with the result that the conditions before noted are reversed, that is, the lower end of the chute descends as it moves out. Three results are obtained: the chute when vertical has its least downward projection into the kier; there is no lifting effect on the cloth; it is possible for the chute to be moved bodily toward the wall of the kier without accompanying descent into the kier;

thereby extending control over the cloth in the most difficult part of its direction.

The chute moves bodily in an arcuate path between frame plates and is guided by the engagement of upper and lower rollers with suitably curved tracks. The chute movement is effected by a simple hoisting mechanism including a reversing gear and means actuated by the movement of the chute to operate the reversing gear.

The cloth is lubricated or floated through the chute by a current of liquid and is discharged at varying angles according to the position of the chute in its swing. The cloth falls in an approximately parabolic line or trajectory as would water from an inclined nozzle or a projectile from a gun. As the level of the pile rises, it is necessary to increase the angle at which the cloth is directed and this is automatically accomplished by simple means operated at each movement of the chute to slightly shift a limit stop engaged by the descending chute for operation of the reversing gear.

In the accompanying drawings which illustrate one embodiment of my improved machine and the manner of carrying out my improved process but to all the details of which the invention is not confined:—

Fig. 1 is a side elevation of the machine with parts broken away in section to more clearly illustrate the construction.

Fig. 2 is a view similar to Figure 1 illustrating the parts in different positions.

Fig. 3 is a front elevation of the machine.

Fig. 4 is a front elevation on an enlarged scale of a part of the controlling mechanism, as seen in Figure 3.

Fig. 5 is a plan view of the lower part of the machine partly in section at about the line 5—5, Figure 3.

Fig. 6 is a side elevation on an enlarged scale of the clutch mechanism used.

Fig. 7 is a front elevation corresponding to Figure 6.

Fig. 8 is a diagrammatic perspective view of the clutch mechanism.

Fig. 9 is a fragmentary detail partly in section on the line 8—8, Figure 1.

Fig. 10 is a diagram illustrating the manner of piling.

Referring more particularly to the drawings, 11 designates a circular frame or base designed to be disposed axially vertical and provided at suitable intervals with lugs 12 in which shouldered pins 13 are mounted with provision for adjustment radially of the base. These pins are adapted to rest upon the lip of a kier 14 with the shoulders engaged with in the lip so as to centre the machine in the kier mouth. The lugs 12 also provide means for the attachment of cables 15 to suspend the machine from an overhead truck. The circular base 11 is provided with an inwardly projecting flange 16 presenting at its inner edge

an upturned rim 17 immediately outside of which is a bearing surface 18. A worm toothed ring gear 19 is disposed within the base approximately co-axial therewith and is provided on its lower side with a pair of flanges 20 and 21 embracing between them the rim 17 of the base whereby the worm gear is held against radial movement within the base. The flange 20 rests on the bearing surface 18 thereby supporting the worm gear. A worm 22 is mounted in any suitable way on the base and meshes with the ring gear 19. The spindle of this worm is driven by a chain 23 or other suitable means from a motor 24 mounted on a bracket 25 carried by the frame. An internally toothed gear or circular rack 26 is fixedly mounted in the base above the worm gear and projects over the worm gear, thereby to hold the same against upward movement out of the base.

The ring gear 19 forms a rotating support for the mechanism hereinafter described which constitutes the conduit and the operating means therefor.

Inward projections 27 from the ring gear carry a pair of main side frames 28 connected thereto by brackets 29 or other suitable means. These frame plates 28 extend above and below the ring gear as clearly seen and at their upper ends are rigidly connected to and rigidly support a preferably cylindrical stationary conduit section 30, which is located in axial alignment with the base and ring gear and which extends downwardly to approximately the level of the ring gear, as clearly shown in Figure 1. A lower conduit section or chute 32 is provided which, at its upper end, encircles the upper section 30. The upper end of the chute 32 is so formed that the chute may be freely moved up and down in an arcuate path relatively to the vertical upper section. The lower end of the chute which is at all times below the upper section is tapered to an outlet of suitable size and shape, and the lower wall of the chute is shaped to facilitate passage of cloth thereover. The chute is in part supported and is at all times guided in its movement by upper and lower rollers 33 on both sides thereof engaging upper and lower tracks or slots 34 and 35 respectively. The rollers may be mounted on the chute and the tracks formed in the frame plates 28 as shown, or vice versa. These slots may be variously shaped according to the exact path and speed variations of movement desired, but the form illustrated has been found suitable and is as follows:—Each upper slot is approximately parabolically curved, the radius being least at the top and gradually increasing toward the bottom where it is greatest. It will be understood that the curvature may include one or more circularly curved portions of appreciable length or may be a succession of circularly curved portions. Each lower slot is mainly

approximately parabolically curved, the radius being least at the bottom and increasing toward a point near the top where the curvature reverses. The general direction of curvature of the upper and lower slots is the same and the slots are arranged substantially in alignment, so that the reversely curved upper portions of the lower slots extend outwardly of the general line of the slots. The slots are preferably so located that the upper and lower ends of each upper slot lie in a single approximately vertical line, while the lower portion of each lower slot lies in an approximately horizontal line, the whole as shown in Figure 1. It will be readily seen that as the chute 32 rises and falls, the engagement of its guiding rollers 33 in the slots 34 and 35 will cause the chute to move in an arcuate path. The special formation of the slots causes the lower end of the chute to move from a position substantially in the axis of the machine to a position close under the shoulder of the kier, as shown in Figure 2. This movement is accomplished by a slight lowering of the lower end of the chute, so that as the chute swings it does not exert any lifting effort on the cloth. This feature can be best appreciated by comparison of the movement indicated in Figure 2 with what would occur if the chute swung from a fixed centre at, say, the upper guide rollers 33. If the centre of oscillation was fixed, it would be necessary, in order for the chute to swing under the shoulder of a kier, to have the fixed centre so low that the end of the chute when in the kier axis would be much lower and would prevent piling cloth in the upper part of the kier. With the construction herein disclosed, it is possible to produce a slightly mounded piling extending at the axis almost up the neck of the kier, so that the capacity of the kier is utilized to the maximum. The peculiar movement of the chute enabling it to reach under the shoulder of the kier has the effect of extending control and support of the cloth nearer to the wall of the kier as the direction of discharge approaches the horizontal.

A second pair of frame plates 36 are rigidly secured by brackets 37 to the lugs 27 of the ring gear and carry the chute operating means. A transverse member 38 is connected between the plates 36 a short distance above the internal gear 26 and serves as an upper bearing for a vertical spindle 39, the lower end of which bears in a lug 40 of the ring gear. Between its two bearings, the spindle 39 has rigidly connected to it a pinion 41 meshing with the internal gear 26. The upper end of the spindle has rigidly connected to it a bevel pinion 42 meshing with a pair of bevel pinions 43 and 44 revolvably mounted on a shaft 45 journalled in bars 46 connected between the frame plates 36.

5 A sliding flanged clutch sleeve 47 is splined

to the shaft 45 and is adapted to mesh with either of the gears 43 or 44. Each end of the clutch sleeve has preferably a single diametrically disposed rib or tooth 47^a adapted to mesh respectively in diametrically cut grooves 43^a and 44^a of the gears 43 and 44 respectively. It will be noted from Figure 8 that the gear 43, which is the chute lifting gear, has only one slot 43^a, while the gear 44 which is the chute lowering gear has a plurality of slots 44^a intersecting at the centre of the gear. The purpose of the different numbers of slots in the gears 43 and 44 is to provide as much lost motion as possible at one reverse in order to prevent the lower end of the chute exactly retracing its former path and to minimize lost motion at the other reverse, in order to reduce as much as possible the dwell of the chute in the axis of the kier.

The forward or outer end of the shaft 45 has fixed thereto a sprocket 48 connected by a chain 49 with a similar sprocket 50, fixedly mounted on a shaft 51 journalled in bars 52 connected between the upper ends of the frame plates 36. Any suitable form of tensioning device, such as the laterally adjustable idler sprocket 49^a, may be provided for the chain to minimize the lost motion or back lash, which must be taken up at each reversal. A shaft 53 is journalled in the frame plates 36 at right angles to the shaft 51 and is driven from the shaft 51 by worm gearing 54. The shaft 53 carries a pair of sprockets 55 over which pass chains 56, corresponding ends of which are connected in any suitable way to the upper end of the chute 32. Most conveniently, the connection is established by means of links 57 pivoted on the centre pins of the upper rollers 33. According to the meshing of the clutch 47, the sprockets 55 are rotated in a direction to either raise or lower the chute 32, lowering being assured by means of a weight 58 connected to the chute. The idle portions of the chains hang quietly between the plates and do not require guiding, but protective housings may be provided if desired.

The clutch is operated by a spring actuated lever or toggle including a lost motion device, the whole shown in detail in Figures 6 and 7. The clutch lever consists of two parts 59 and 60, each loosely mounted on a shaft 61 extending between the frame plates 36. The part 59 is approximately H-shaped, as seen in Figure 7, and is mounted at its lower end on the shaft 61. The part 60 is mounted intermediate its ends on the shaft 61 and the upper end is embraced between the side members of the part 59 and is bifurcated to receive between the bifurcations 62 thereof the cross bar 63 of the H-shaped part 59. The space between the bifurcations 62 is such that there is considerable lost motion permitted, as will be readily seen in Figure 6. The lower end of the lever part 60 is jawed

to embrace the clutch sleeve 47 and carries pivotally mounted shoes 64 running between the sleeve flanges. A shaft 65 is journalled between the frame plates 36 above the shaft 61 and has rigidly secured thereto an arm 66 slidable through a block 67 trunnion-mounted between the upper ends of the side members of the lever part 59. A helical spring 68 is compressed between the block 67 and a shoulder on the arm 66 adjacent the shaft 65. By partial rotation of the shaft 65, the arm 66 may be moved from the inclined position shown in full lines Figure 6 nearly to the neutral position shown in broken lines, without producing any movement of the lower end of the clutch lever, owing to the travel of the cross bar 63 between the bifurcations 62. This permits the jointed lever mechanism to be moved through the neutral position to an opposite inclination before the clutch is unmeshed, for example, from the pinion 43, so that the spring will exert itself to throw the clutch into mesh for example with the pinion 44. In other words, the lost motion connection permits the mechanism to move through the neutral position, even if the clutch should not mesh when thrown, so that when the teeth of the clutch and grooves of the pinion do come into meshing relation, the spring mechanism will be sufficiently beyond the neutral position to be capable of effecting the desired meshing. This mechanism renders the clutch infallible in operation as is absolutely necessary.

The shaft 65 is rotated as is necessary to shift the clutch by the movement of the chute 32 in the following manner. An arm 69 is rigidly secured to the shaft and carries at its extremity a rod 70, upon which are mounted upper and lower adjustable stops 71 and 72 respectively. Preferably, the rod 70 is threaded and the stops 71 and 72 are nuts co-operating with the threads of the rod. A slide 73 is mounted on the rod between the upper and lower stops and is pivotally connected to an operating lever 74 at a point intermediate the ends thereof. This lever is fulcrumed at one end at any suitable point, for example, on the shaft 61 and is connected at the opposite end of the chute 32, for example, to the centre pin on an upper roller 33. At the fulcrumed end, the lever 74 is slotted as at 75 to compensate for the location of the shaft 61 eccentrically with respect to the curvature of the slot 34, which determines the movement of the lever. The lever 69 is preferably provided with a counter-balance weight 76 on the opposite side of the shaft 65 from the mechanism just described, so as to render the actuating mechanism as sensitive as possible. As the chute moves up and down, it shifts the slide 73 on the rod 70, bringing the same into contact with the stops 71 and 72 alternately and thereby imparting longitudinal movement to the rod, which then op-

erates the arm 69 to rotate the shaft 65 and initiate shifting of the clutch, so as to change the direction of movement of the chute.

It has been stated that the amplitude of movement of the chute 32 is automatically increased as piling progresses. In each upward movement of the chute, the rollers 33 travel to, or nearly to, the upper ends of the slots 34 and 35, so as to bring the lower end of the chute into, or very close to, the axis of the kier and therefore vertically beneath the upper section 30. The exact limit of upward movement and therefore of the approach of the chute end to the axis of the kier is determined by adjustment of the upper stop 71. When filling of the kier is commenced, the angle subtended at the piling mechanism by the radius of the kier at the bottom thereof is comparatively small and but little movement of the spout is required to direct the cloth at such an angle that its trajectory or line of travel (indicated in Figure 10) will extend to the wall of the kier. In order to limit the angular movement of the chute to obtain only this degree of lateral projection, the lower stop 72 is positioned well upon the rod 70. The lower stop 72 is held against rotation by a link 77 pivotally connected thereto and running in a guide 78 (Figure 3) carried by one of the frame plates 36. Mechanism is provided operating automatically to slowly rotate the rod, so that the irrevoluble nut 72 or bottom stop gradually shifts down as the piling progresses, allowing the chute 32 to slightly increase its amplitude of angular movement at each descent. This mechanism comprises a pawl 79 adjustably mounted on the slide 73 by means of a threaded spindle 80 and nut 81, the said pawl meshing with a ratchet wheel 82 fixed on a spindle 83 and connected by mitre gears 84 with the rod 70 which for the purpose is journalled in a stirrup 85 carrying the spindle 83. This stirrup serves to connect the rod to the arm 69. With the pawl to the right of the rod as shown, in the final part of each upward movement of the chute 32, the pawl 79 rotates the ratchet wheel 82 a fraction of a revolution determined by the vertical adjustment of the pawl relatively to the slide 73 and this rotation is communicated as already described to the rod 70, causing the same to partially rotate within the irrevoluble stop nut 72, so that the same is shifted slightly down on the rod. The pawl may be placed to the left of the rod, in which case rod rotation is effected on commencement of the downward movement. A rebound pawl 86 is carried by the stirrup to hold the ratchet wheel 82 against reverse rotation when the pawl 79 trails over it. A hand wheel 87 is provided on the spindle 83 to permit of manual adjustment of the lower stop 72 by rotation of the spindle. When the stop 72 is at its lowermost position, the rollers 33 travel substantially to the lower ends of

the slots 34, thereby permitting the chute a maximum amplitude of movement and a maximum lateral reach under the shoulder of a kier, so that cloth will be directed to reach the wall of the kier only slightly below the level of the end of the chute. By slight alteration in the shape of the slots 34 and 35, the chute may be caused to swing more nearly to horizontal position than shown, but it will be understood that the amplitude of chute swing is governed by the length of neck of the kier with which it is to be used.

In order to supply liquid for lubricating and loading the cloth to facilitate its movement through the conduit, a stationary funnel 88 is mounted upon the upper end of the conduit section 30 relatively revoluble with relation to the section, so that the same may rotate under the funnel, which is held stationary by its liquid supply pipe 89 clamped to a post 90 springing from the motor bracket 25. The lower end of the funnel is provided with an annular channel 90 into which fluid is supplied through the pipe 89. The bottom of the funnel presents a shoulder 91 facing downwardly into the conduit and provided with a series of apertures 92 leading from the annular channel 90. These apertures are so disposed as to compel discharge of the fluid in the form of a series of jets which converge to the axis of the conduit section 30 at a point below the funnel 88. A rope of cloth passing through the conduit is caught by the downwardly converging jets of liquid, which beat upon it from all sides, thus causing a rapid and thorough impregnation of the cloth as well as a loading thereof. The converging jets also serve to centre the cloth in the conduit and further provide a film of liquid outside the cloth, which acts to lubricate or float the same through the chute. By this means, the cloth may be passed through the conduit at very high lineal speed without danger of blocking even when the chute 32 is at its maximum inclination.

Briefly described the operation of the machine illustrated is as follows:—assuming the chute 32 to be drawn up to the maximum extent and the clutch properly positioned for lowering of the chute. The motor drives the worm 22 which in turn slowly rotates the ring gear 19 and with it all the mechanism mounted on it. The pinion 41 is by rotation of the ring gear caused to travel over the rack 26 and, through the mitre gearing, chain gearing and worm gearing, rotates the sprockets 55 in clockwise direction, so that the chute 32 is lowered. The upper and lower guide rollers 33 thereof travel down in the slots 34, 35, causing the chute to travel in an arcuate path as it descends. In the meantime, roped cloth is being passed into the machine through the funnel 88 and flushed through the conduit sections 30 and 32 by flow of liquid. The cloth is discharged at an

angle determined by the position of the chute 32 and travels through a curved path or trajectory between the chute and the kier bottom or cloth already piled in the kier. With a ratio of gearing such as shown, the machine rotates several times about its axis, while the chute is descending or ascending. The result is that the cloth is directed so that it falls in an approximately spiral line. Owing to the curvature of the upper ends of the slots 34, 35, the upper end of the chute is at first moved to the right, while the lower end is moved sharply and quickly to the left, as will be seen from Figure 1. In the intermediate part of the movement the rollers are travelling in the medial portions of the slots and the chute swings less sharply. In the final part of the descent, the lower rollers run sharply to the left in the bottoms of the slots 35, while the upper rollers drop nearly vertically in the lower parts of the slots 34, so that the chute moves much more to the left than it does downwardly. This formation of the slots 34 and 35 causes the angular speed of the chute (in its arcuate path) to be greatest at the commencement of its descent and to diminish as it descends. The effect produced by the compounding of this movement with the rotation of the whole machine is that the cloth is laid in a roughly spiral line, the inner turns of the spiral being spaced further apart than the outer turns, which are adjacent the wall of the kier. The lineal speed of the cloth is materially greater than the lineal speed of the lower end of the chute travelling in its spiral path, with the result that the rope of cloth instead of being stretched smoothly is bunched up, forming a mound or pile of spiral shape. When the chute reaches the extremity of its downward movement, the mechanism reverses as already described and the chute commences to rise. The ratio of the gearing is preferably such that the end of the chute does not exactly retrace its original path but follows a similar path slightly out of register with the former, so that the cloth piled during the inward swing of the chute tends to fill spaces between the turns of the spiral of cloth first made. This motion continues. Each time the chute rises it rotates the rod 70 to a suitable extent, thus causing the stop 72 to move down on the rod and permit a slightly greater descending movement the next time. In this way, the angular movement of the chute in its arcuate path is gradually increased as the piling level rises toward the machine. At the same time the increased descending movement enables the chute to reach slightly further under the shoulder of the kier and to approach more nearly to the horizontal. By reason of these two occurrences, the chute is enabled to so direct the cloth that at the extreme of movement the cloth will fall at the periphery of the kier. The net result is that the various

layers of cloth laid in the kier average one another and the top layer is approximately horizontal or slightly raised in the centre. Owing to the small vertical distance required for operation of the machine, cloth may be piled in the kier nearly up to the shoulder.

While I have described and illustrated one embodiment of my invention, I wish it to be understood that numerous modifications of detail may be made without departing from the spirit of the invention, particularly in the ratio of the speed of rotation to the speed of chute swing. By relatively increasing the speed of chute swing, the spiral traced by the piling cloth may be caused to extend from the centre to the wall of the kier in less than one revolution of the machine and, in cases where the speed of the cloth is variable, shorter spirals are preferable.

25 I claim:

1. In a cloth piling machine, a conduit comprising an upper section, and a single lower chute section slidably and swingingly related to the upper section whereby the lower section may move into and out of axial alignment with the upper section.

2. In a cloth piling machine, a conduit comprising an upper section and a rigid lower chute section slidably and swingingly related to the upper section and adapted to swing from a rising and falling axis of oscillation.

3. In a cloth piling machine, a conduit comprising an upper vertical section and a lower chute section telescopically related to the upper section, and adapted to swing alternately from and towards the axial line of the upper section, and simultaneously with such movement to move bodily alternately downwards and upwards in arcuate paths.

40 4. In a cloth piling machine, a conduit comprising an upper vertical section and a lower chute section telescopically related to the upper section, and adapted to oscillate alternately from and towards the axis of the upper section from an axis of oscillation, falling during the outward swing, and rising during the inward swing.

5. In a cloth piling machine, a conduit comprising an upper vertical section and a lower chute section, and adapted to swing alternately from and towards the axial line of the upper section, and simultaneously with such movement to move bodily alternately downwards and upwards in arcuate paths, the amplitude of movement of the chute increasing with each successive descent.

6. In a cloth piling machine a swinging chute adapted to deflect a downwardly moving strand of cloth from a vertical path laterally into a substantially parabolic path said chute moving bodily downward when moving in the direction of cloth movement during such deflection, but at lower speed.

7. In a cloth piling machine, a swinging chute adapted to deflect a downwardly mov-

ing strand of cloth from a vertical path laterally into a substantially parabolic path, said chute moving bodily downward when moving in the direction of the cloth movement during such deflection, but at lower speed, the extent of the chute swing and movement being greater in each successive deflection of the cloth.

8. In a cloth piling machine, a conduit comprising an upper section and a single lower chute section slidably and swingingly related to the upper section, and means for moving the chute.

9. In a cloth piling machine, a conduit comprising an upper vertical section and a lower chute section telescopically related to the upper section, and adapted to swing alternately from and towards the axial line of the upper section, and simultaneously with such movement, to move bodily alternately downwards and upwards in arcuate paths, and means for raising and lowering chute, and means for guiding the chute during its rise and fall to cause the swinging movement thereof.

10. In a cloth piling machine, a conduit comprising an upper vertical section and a lower chute section, telescopically related to the upper section, and adapted to swing from and toward the axial line of the upper section, and simultaneously with such movement to move bodily alternately downwards and upwards in arcuate paths, a frame member past which the chute member moves, means for raising and lowering the chute member, guide rollers on one of said members, and tracks on the other of said members disposed to be engaged by the guide rollers to guide the chute member during its rise and fall, and cause the swinging movement thereof.

11. In a cloth piling machine, a conduit comprising an upper vertical section of a lower chute section telescopically related to the upper section, and adapted to swing alternately from and towards the axial line of the upper section, and simultaneously with such movement to move bodily alternately downwards and upwards in arcuate paths, a frame member past which the chute member moves, means for raising and lowering the chute member, upper and lower guide rolls on one of said members, upper and lower curved tracks on the other of said members, engaged by the guide rolls, said tracks being generally curved in the same direction, but the upper end of the lower track being curved oppositely to the lower part and the lower end of the lower track extending approximately horizontally.

12. In a cloth piling machine, a conduit comprising an upper vertical section and a lower chute section telescopically related to the upper section, and adapted to swing alternately from and towards the axial line of the upper section, and simultaneously with such movement to move bodily alternately downwards and upwards in arcuate paths,

and means for moving the chute as herein set forth.

13. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, and means for rotating the whole conduit.

14. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, means for moving the chute as herein set forth, and means for rotating the whole conduit.

15. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, means for raising and lowering the chute, means for guiding the chute during its rise and fall to cause the swinging movement thereof, and means for rotating the whole conduit simultaneously with the movements of the chute section thereof.

16. In a cloth piling machine, a conduit comprising an upper section and, a lower chute section slidably and swingingly related to the upper section, and a rotatable support for the conduit.

17. In a cloth piling machine, a conduit comprising an upper section and a lower chute section slidably and swingingly related to the upper section, a rotatable support for the conduit, and means operated by rotation of said support for moving the chute section of the conduit.

18. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, a rotatable support for the conduit, means operated by the rotation of the support for raising and lowering the chute, and means on said support for guiding the chute during its rise and fall to cause the swinging movement thereof.

19. In a cloth piling machine, a conduit comprising an upper section and a lower chute section slidably and swingingly related to

the upper section, a rotatable support for the conduit, a circular rack concentric with said support, means on the support for moving the chute including a pinion meshing with the rack whereby the chute is moved upon rotation of the support.

20. In a cloth piling machine, a conduit comprising an upper section and a lower chute section slidably and swingingly related to the upper section, a rotatable support for the conduit, a circular rack concentric with the support, a sprocket carried by the support, a chain connected to the upper end of the chute operatively engaging the sprocket and means operated by rotation of the support for rotating said sprocket.

21. In a cloth piling machine, a conduit comprising an upper section and a lower chute section slidably and swingingly related to the upper section, a rotatable support for the conduit, a circular rack concentric with the support, a sprocket carried by the support, a chain connected to the upper end of the chute operatively engaging the sprocket, and means operated by rotation of the support for rotating said sprocket, and means operated by the chute for periodically reversing the direction of sprocket rotation.

22. In a cloth piling machine, a conduit comprising an upper section and a lower chute section slidably and swingingly related to the upper section, a sprocket, a chain connected to the chute and operatively engaging the sprocket, and means to rotate the sprocket thereby to move the chute.

23. In a cloth piling machine, a conduit comprising an upper section and a lower chute section slidably and swingingly related to the upper section, a sprocket, a chain connected to the chute and operatively engaging the sprocket, means to rotate the sprocket thereby to move the chute, and means actuated by movement of the chute controlling the sprocket rotating means to periodically effect reversal of the direction of sprocket rotation.

24. In a cloth piling machine, a conduit comprising an upper section and a lower chute section slidably and swingingly related to the upper section, a sprocket, a chain connected to the chute and operatively engaging the sprocket, means to rotate the sprocket thereby to move the chute, and means actuated by movement of the chute controlling the sprocket rotating means to periodically effect reversal of the direction of sprocket rotation, said chute actuated means including automatically operating means for gradually increasing the periods between reversals of sprocket rotation.

25. In a cloth piling machine, a conduit comprising an upper vertical section and a lower chute section telescopically related to the upper section and adapted to swing alternately from and towards the axial line of the

- upper section, and simultaneously with such movement to move bodily alternately downwards and upwards in arcuate paths, a sprocket, a chain connected to the chute and operatively engaging the sprocket means to rotate the sprocket thereby to raise or lower the chute, and means for guiding the chute in an arcuate path as it rises or falls thereby to swing the same. 70
13. 26. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, a sprocket, a chain connected to the chute and operatively engaging the sprocket, means to rotate the sprocket thereby to raise or lower the chute, means for guiding the chute in an arcuate path as it rises or falls thereby to swing the same, and means actuated by movement of the chute controlling the sprocket rotating means to periodically effect reversal of the direction of sprocket rotation. 75
15. 27. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, a sprocket, a chain connected to the chute and operatively engaging the sprocket, means to rotate the sprocket thereby to raise or lower the chute, means for guiding the chute in an arcuate path as it rises or falls thereby to swing the same, and means actuated by movement of the chute controlling the sprocket rotating means to periodically effect reversal of the direction of sprocket rotation. 80
17. 28. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, a sprocket, a chain connected to the chute and operatively engaging the sprocket, means to rotate the sprocket thereby to raise or lower the chute, means for guiding the chute in an arcuate path as it rises or falls thereby to swing the same, and means actuated by movement of the chute controlling the sprocket rotating means to periodically effect reversal of the direction of sprocket rotation, said chute actuated means including automatically operating means for gradually increasing the periods between reversals of sprocket rotation. 85
19. 29. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, a rotatable support for the conduit, a sprocket carried by the support, a chain connected to the chute and operatively engaging the sprocket, a circular rack concentric with the support, means to rotate the sprocket upon rotation of the support to raise or lower the chute including a pinion on the support meshing with the rack, and means for guiding the chute in an arcuate path as it rises or falls thereby to swing the same. 90
21. 30. In a cloth piling machine, a conduit comprising an upper section and a lower chute section slidably and swingingly related to the upper section, and means to effect the sliding movement of the chute comprising a sprocket, a chain connected to the chute operatively engaging the sprocket, a gear train driving the sprocket including oppositely rotating gears revoluble on a common shaft, a clutch splined to the shaft to mesh with either of said gears, a spring actuated clutch throw lever and a chute operated lever initiating movement of the clutch throw lever. 95
23. 31. In a cloth piling machine, a conduit comprising an upper section and a lower chute section slidably and swingingly related to the upper section, and means to effect the sliding movement of the chute comprising a sprocket, a chain connected to the chute operatively engaging the sprocket, a gear train driving the sprocket including oppositely rotating gears revoluble on a common shaft, a clutch splined to the shaft to mesh with either of said gears, a spring actuated clutch throw lever, an operating arm for said lever, a rod connected to said arm, stops on the rod, a slide on the rod between said stops, an actuating member connected to the chute and to said slide to move the same against the stops and impart chute movement through the rod and arm to the clutch throw lever. 100
25. 32. A device according to claim 31, in which the rod is threaded and one of the stops is a nut held irrevoluble, in combination with means carried by the slide to partially rotate the rod once in each cycle of chute movement thereby to shift the stop on the rod to vary the amplitude of chute movement necessary to effect operation of the clutch. 105
27. 33. A device according to claim 31 in which the rod is threaded and one of the stops is a 110
29. 34. A device according to claim 31 in which the rod is threaded and one of the stops is a 115
31. 35. A device according to claim 31 in which the rod is threaded and one of the stops is a 120
33. 36. A device according to claim 31 in which the rod is threaded and one of the stops is a 125
35. 37. A device according to claim 31 in which the rod is threaded and one of the stops is a 130

nut held irrevoluble, in combination with a pawl adjustably carried on the slide, a ratchet wheel, and gear connection between the ratchet wheel and the rod.

5 34. A device according to claim 30, in which the clutch throw lever comprises a pair of parts pivotally related at the fulcrum point of the lever, one of said parts being bifurcated and the other part including a web disposed between the bifurcations of the first part with limited movement therebetween, in combination with a block pivotally mounted on the lever on the opposite side of the fulcrum thereof from the clutch, an operating 10 shaft, an arm rigidly connected to the shaft and a spring on the arm in compression between the shaft and block.

15 35. In a cloth piling machine, a conduit comprising an upper vertical section and a lower chute section telescopically related to the upper section and adapted to swing alternately from and towards the axial line of the upper section and simultaneously with such movement to move bodily alternately downwards and upwards in arcuate paths, a base 20 to rest on a kier, a conduit support revolubly mounted in the base, frame plates rigidly connected to the support and to the upper section of the conduit, sprockets carried by the support, chains connected to the lower conduit section operatively engaging said sprockets, a circular rack concentric with the rotatable support and means mounted on the support operably engaging the rack and operated thereby upon rotation of the support to rotate the sprockets.

25 36. In a cloth piling machine, a conduit comprising an upper vertical section and a lower chute section telescopically related to the upper section and adapted to swing alternately downwards and upwards in arcuate paths, a base to rest on a kier, a conduit support revolubly mounted in the base, frame plates rigidly connected to the support and to the upper section of the conduit, sprockets carried by the support, chains connected to the lower conduit section operatively engaging said sprockets, a circular rack concentric with the rotatable support, and means mounted on the support operably engaging the rack and operated thereby upon rotation of the support to rotate the sprockets, said frame plates being disposed on opposite sides of the conduit and having upper and lower cam slots therein and upper and lower rollers on the lower conduit section engaging in the plate slots to guide the lower conduit section.

30 37. In combination with a device according to claim 35, means connected to the lower section of the conduit to control the sprocket operating means.

35 38. In a cloth piling machine, a conduit comprising an upper vertical section and a lower chute section telescopically related to

the upper section and adapted to swing alternately from and towards the axial line of the upper section and simultaneously with such movement to move bodily alternately downwards and upwards in arcuate paths, a base to rest on a kier, a conduit support revolubly mounted in the base, frame plates rigidly connected to the support and to the upper section of the conduit, sprockets carried by the support, chains connected to the lower conduit section operatively engaging said sprockets, a circular rack concentric with the rotatable support and means mounted on the support operably engaging the rack and operated thereby upon rotation of the support to rotate the sprockets, said means including a reversing gear set, in combination with a spring actuated reversing means for the gear set, including an operating arm, a rod connected thereto, stops on the rod, a slide on the rod between the stops, a lever connected to the lower conduit section and to the slide whereby movement of the lower conduit section sets in operation the spring actuated reversing means.

40 39. In a cloth piling machine, a conduit comprising an upper vertical section and a lower chute section telescopically related to the upper section and adapted to swing alternately from and towards the axial line of the upper section and simultaneously with such movement to move bodily alternately downwards and upwards in arcuate paths, a base to rest on a kier, a conduit support revolubly mounted in the base, frame plates rigidly connected to the support and to the upper section of the conduit, sprockets carried by the support, chains connected to the lower conduit section operatively engaging said sprockets, a circular rack concentric with the rotatable support and means mounted on the support operably engaging the rack and operated thereby upon rotation of the support to rotate the sprockets, said means including a reversing gear set, in combination with a spring actuated reversing means for the gear set, including an operating arm, a threaded rod connected to the arm, upper and lower stops threaded on the rod, means holding the lower stop against rotation, a slide on the rod between the stops, a pawl adjustably mounted on the slide, a ratchet wheel to be engaged and partially rotated by the pawl once in each cycle of movement of the lower conduit section, and gear connection between the ratchet wheel and rod.

45 40. In combination with a device according to claim 39, means for manually rotating the ratchet wheel independently of the pawl.

50 41. A device according to claim 35, in which the sprocket operating means includes a pinion meshing with the rack, a bevel gear rigidly connected to the pinion, a shaft, a pair of bevel gears loosely mounted on said shaft

meshing with the first pinion on opposite sides of the centre thereof, a clutch sleeve splined to the shaft between said gears and operatively engageable with either gear, a further shaft, gear connection between said further shaft and the sprockets, and a chain operatively connecting said two shafts.

42. A device according to claim 35, in which the sprocket operating means includes a pinion meshing with the rack, a bevel gear rigidly connected to the pinion, a shaft, a pair of bevel gears loosely mounted on said shaft meshing with the first pinion on opposite sides of the centre thereof, one gear of the pair being formed with a single diametrically disposed slot in its hub and the other gear of the pair being formed with a plurality of such slots, a clutch sleeve splined to the shaft between said gears and operatively engageable with either gear, each end of the clutch sleeve being formed at each end with a single diametrically disposed tooth to engage in the gear slots, a further shaft, gear connection between said further shaft and the sprockets, and a chain operatively connecting said two shafts.

43. In a cloth piling machine, a conduit comprising an upper vertical section and a lower chute section telescopically related to the upper section and adapted to swing alternately from and towards the axial line of the upper section and simultaneously with such movement to move bodily alternately downwards and upwards in arcuate paths, and means for moving the chute including reversing mechanism operable to change the direction of chute movement more rapidly at the upper limit of movement than at the lower.

44. In a cloth piling machine, a conduit comprising an upper vertical section and a lower chute section telescopically related to the upper section and adapted to swing alternately from and towards the axial line of the upper section and simultaneously with such movement to move bodily alternately downwards and upwards in arcuate paths, means for raising and lowering the chute, and means for guiding the chute during its rise and fall to cause the swinging movement thereof, said guiding means being operable to cause the chute to swing more rapidly when adjacent the said axial line than when remote therefrom.

45. In a cloth piling machine, a conduit comprising an upper vertical section and a lower chute section telescopically related to the upper section and adapted to swing alternately from and towards the axial line of the upper section and simultaneously with such movement to move bodily alternately downwards and upwards in arcuate paths, means for raising and lowering the chute, and means for guiding the chute during its rise and fall to cause the swinging move-

ment thereof, said guiding means being operable to cause the chute to swing more rapidly as it approaches the said axial line and more slowly as it swings away from the axial line.

46. In a cloth piling machine, a conduit comprising an upper vertical section and a lower chute section telescopically related to the upper section and adapted to swing alternately from and towards the axial line of the upper section, and simultaneously with such movement to move bodily alternately downwards and upwards in arcuate paths, means for raising and lowering the chute, and means for guiding the chute during its rise and fall to cause the swinging movement thereof, said guiding means being operable to vary the angular speed of the chute in its swinging movement.

47. A process of piling roped cloth in a cylindrical kier or the like, which comprises, feeding the cloth downwardly at the axis of the kier and deflecting the cloth at the top of the kier through regularly varying angles and at regularly varying speed of angular deflection, the amplitude of the angle of deflection being increased as the level of the pile rises, thereby causing the cloth to fall along a parabolically curved spiral path extending at all piling levels from the axis to the circumference of the kier.

In witness whereof, I have heretunto set my hand.

JOHN J. LYTH.
